DESIGN FOR A POWDER DISPENSER OR SIMILAR ARTICLE

Frank McIntosh, New York, N. Y., assignor to Letheric Incorporated, New York, N. Y., a corporation of New York

Application May 16, 1941, Serial No. 100,980

Term of patent 3½ years

To all whom it may concern:

Be it known that I, Frank McIntosh, a citizen of the United States, residing at New York city, in the county of New York and State of New York, have invented a new, original, and ornamental Design for a Powder Dispenser or Similar Article, of which the following is a specification, reference being had to the accompanying drawing, forming part thereof.

In the drawing:

Fig. 1 is a top plan view of a powder dispenser
embodying my new design;

Fig. 2 is a front elevational view; and

Fig. 3 is a rear elevational view thereof.

I claim:

The ornamental design for a powder dispenser or similar article, substantially as shown.

FRANK McINTOSH.
